ATTORNEY

UNITED STATES PATENT OFFICE

THEODORE CARLSON, OF SEATTLE, WASHINGTON

CLAMSHELL BUCKET

Application filed August 1, 1927. Serial No. 209,812.

This invention relates to clamshell buckets such as employed for excavating and elevating material.

The object of the invention is to provide a bucket of this character which will be strong and durable in its construction and efficient in operation.

A further object of the invention is to provide a two-line controlled bucket wherein the scoop members are adapted to be regulated for rapid and slow closing movements when excavating or taking in a load, and wherein the two line control is adapted to regulate the speed and extent of the opening movements of the bucket members for depositing the load.

A further object is to provide a bucket wherein the controlling lines are adapted to be utilized for holding the scoops in positions most advantageous for digging.

A further object of the invention is to provide a bucket wherein the parts are arranged to enable the hoisting line to apply power most advantageously to effect closing movements between the scoops.

Other objects and advantages of the invention will appear in the following description.

The invention consists in the novel construction, adaptation and combination of parts hereinafter described and claimed.

In the accompanying drawing,—

Figure 1 is a longitudinal vertical section of a clamshell bucket embodying the present invention, the bucket being illustrated in its closed relation; Fig. 2 is a side elevation of the same illustrated in its open relation; Fig. 3 is an end elevation of the bucket when closed; Fig. 4 is a plan view of the bucket scoop members; and Fig. 5 is a detail horizontal sectional view to show the preferred manner of hingedly connecting the yoke members together.

In said drawing, the reference numerals 10 represent complementary scoop members which, as shown are each reinforced at its top by a transverse bar element 11 secured to the respective end wall 12 of a scoop and having side arms 13 which are secured to the respective side walls 14.

Between said side arms each scoop rein-

forcement is provided with a third arm 15, hereinafter termed a closing arm, which is integral with the respective bar element 11 and from about the middle of the bar extends inwardly and upwardly of the respective scoop, the free ends of both closing arms being pivotally connected together by means of a pin 16 located at the midwidth of the bucket.

Supporting said scoops are two companion yokes, one yoke for each scoop, both yokes being pivotally connected together at their upper ends, and pivotally connected with the respective scoops at their lower ends.

As shown, a yoke comprises a pair of bar elements 17 which are held in spaced apart relation near their lower ends as by means of a bridge element 18 to accommodate a closing-arm therebetween. A yoke is also provided with side arms 19 which terminate in parallel lower end portions 20 which are adapted to extend into cavities 21 (Fig. 4) provided between the side walls 14 of the associated scoop and off set portions 13¹ of the side arms 13 of the scoop's reinforcement.

Hinge pins 22 extending through the respective side walls 14 and the arm portions 13 of a reinforcing member serve to hingedly connect the end portions 20 of the yokes to the corners of the bucket. The yokes are also hingedly connected to the scoops by means of pins 23 extending through the respective bar elements 17 and closing arms 15.

The upper ends of said yokes are pivotally connected with each other and to an apertured block 24 as by means of trunnions upon the latter engaging within the yoke bars 17 at opposite sides of the block; or, instead of trunnions, axially aligned pins 25 (Fig. 5) may be utilized. As shown, the pins 25 extend through bushings 27 provided in holes of said yoke bars and into sockets provided in the block. The pins 25 in the illustrated embodiment, are secured to the respective bushings by set pins 26, the bushings being held against lateral displacement by the provision of bushing-flange elements 27¹.

The aperture 28 of the block 24 serves as a guide way for a cable 29, conventionally known as the hoisting line, the lower end of which is connected to the pin 16 of the clos-

ing arms 15 as by means of a clevis 30 having therein a conical receptacle 31 (Fig. 1) in which the expanded end of the hoisting line is secured by known means of a lead filling. Said hoisting line in addition to its function of raising, lowering and supporting the bucket in the air also serves to effect the closing of the bucket. The opening of the bucket is effected by what may be termed the opening line, the same comprising a cable 32 provided at its lower end with an eye or ring 33 through which is reeved a sling 34. From said ring the sling extends as branches 35 about the inner and outer sides respectively of guide sheaves 36 and 37 provided for both yokes whence the extremities of the sling are secured to eye attachments 38 rigid with the respective buckets 10.

As shown the sheaves 36 are positioned mainly between the bar elements 17 of the respective yokes and the other guide sheaves, 37, are positioned in outriggers 39 connecting the main portions of the referred to bar elements with the bridge elements 18.

The object of offsetting the guide sheaves 37 is to have the ends of the sling branches 35 led most advantageously to the scoops for drawing the same apart when opening the bucket either for digging or dumping purposes.

Besides serving as offsetting supports for the guide sheaves 37, the outriggers 39 serve as abutments to limit the bucket opening movements of the scoops, so that the latter is provided with a firm backing when the bucket is lowered in its full open relation to facilitate digging into hard material.

In Fig. 1, 18¹ indicates bridge pieces which may be used, if desired for connecting the bar elements 17 of each yoke together near their upper ends.

The operation of the invention is as follows:

For digging or scooping up a load the bucket is lowered in its Fig. 2 relation upon the material cutting into the same according to its hardness and the speed at which the bucket is permitted to drop. In being lowered for digging, the bucket is kept open by maintaining a tension upon the line 32 (Fig. 1). Such tension upon the line 32 acts through the branches 35 thereof to retain the bucket scoops in their relative lowered positions substantially as shown in Fig. 2, the closing arms 15 being extended so that the axis of the pivotal pin 16 therefor will be in or slightly below a horizontal plane in which are located the axes of the hinge pieces 22 of the scoops 10.

Thus arranged the closing arms coact with the opening line connections 35 to retain the scoops in positions best adapted for digging.

For closing the bucket, the hoisting line 29 is actuated to swing the closing arms 15 upwardly, which—acting as toggle links—

serve to draw the yokes toward each other coincidently with the swinging of the scoops about the pins 22 and 23 which hinge the scoops to the yokes.

For elevating the bucket both of the lines 29 and 32 may be utilized.

The load carried in the bucket is discharged by slackening, more or less, the hoisting line while maintaining more or less tension on the bucket opening line 32, the action of gravitation serving to effect the opening of the bucket supplemented by the effective power which may be applied through the line 32.

The hoisting line 29 by being guided in the apertured block 24 at the top of the yoke assembly from the bottom of which depend the bucket scoops assures that the bucket will be held in an upright position when under the control of the hoisting line.

The branches 35 of the bucket opening line 32 are guided close to the central portion of the top of the yoke assembly by means of the sheaves 36, hence the bucket will also be held in an upright position when under the control of the line 32.

The construction, operation, and advantages of the invention will, it is thought, be understood from the foregoing description.

What I claim, is:—

1. In a clamshell bucket, two scoop members, each scoop having a reinforcing frame provided with side elements and a rigid arm extending inwardly and upwardly of the scoop, a pin pivotally connecting the upper ends of said arms together, bucket supporting means comprising companion yokes hingedly connected at their lower ends to the outer portions of the respective scoops between the side walls of the latter and the side elements of the respective reinforcing frames, means for pivotally connecting the upper portions of both yokes together, a bucket hoisting cable connected to said pin, a bucket opening cable having leads connected to the respective scoops, and means associated with the yokes for guiding the hoisting cable and the leads of the bucket opening cable through the upper portion of the yoke assembly.

2. In a clamshell bucket, the combination of the bucket scoops, pivotally connected yokes supporting said scoops and hingedly connected thereto, a hoisting cable connected to both of said scoops between said hinge connections, means provided in proximity of the pivoted connection of the yokes for guiding said hoisting cable, a bucket opening cable having leads passing about guide pulleys mounted upon said yokes, means rigid with the outer sides of the scoops to which the ends of said leads are connected, and means provided upon said yokes for limiting the outward movement of the respective scoops with respect to their hinge connections with the yokes.

3. In a clamshell bucket, the combination

with scoop members, yoke members hinged-
ly connected at their lower ends to the re-
spective scoops, a bucket-closing cable oper-
atively connected to said scoops, a guide pro-
vided for said cable, means provided on said
guide for pivotally connecting the upper
ends of the yokes, a bucket-opening cable,
guide sheaves for the bucket-opening cable,
and means protruding from said yokes for
10 supporting said sheaves in offset
relation with the respective yokes, said sheaves sup-
porting means being positioned to serve as
stops to limit the swinging movements of the
scoops with respect to the hinge connections
15 thereof with the yokes.

4. In a clamshell bucket, the combination
with the bucket scoops, of a yoke support
for each scoop, said yokes being pivotally
connected together at their upper ends, pins
20 pivotally connecting the lower ends of said
yokes to the side walls of the respective
scoops, frames rigid with the respective
scoops and serving to reinforce the side walls
thereof, arms provided on said frames and
25 adapted to serve as toggle devices to effect
movements of said yokes for swinging the
scoops bodily toward and from each other,
said arms also serving to swing the respec-
tive scoops about their hinge connections
30 with the respective yokes, a hoisting line con-
nected with both of said arms for actuating
the same, and a bucket opening cable having
connections with both of said scoops at the
opposite sides of the hinge connections of the
35 respective scoops from the connection of the
hoisting cable with said arms.

5. In a clamshell bucket, the combination
with the scoop members, scoop supporting
means hingedly connected to the side walls
40 of the respective scoops and arranged to per-
mit movement of the scoops bodily toward
and from each other, arms rigid with the re-
spective scoops intermediate the widths of
the latter, means to pivotally connect the
45 upper ends of said arms, a bucket-closing
cable connected to said pivoting means for
swinging the scoops about the axes of their
hinge connections with said supporting
means, said cable also serving to draw said
50 means and the scoops into bucket closing re-
lation, and bucket opening means secured to
the outer sides of said scoop members for
effecting the spreading apart of the buckets
and the swinging of the scoops about the
55 axes of said hinge connections.

6. In a clamshell bucket, the combination
with the scoop members, yoke members
hingedly connected at their lower ends to the re-
spective scoops, a bucket-closing cable
60 operatively connected to said scoops, a guide
provided for said cable, means provided on
said guide for pivotally connecting the
upper ends of the yokes, a bucket-opening
cable, guide sheaves for the bucket-opening
65 cable, and means protruding from said

yokes for supporting said sheaves in offset
relation with the respective yokes.

Signed at Seattle, Washington, this 12th
day of July, 1927.

THEODORE CARLSON.
